UNITED STATES PATENT OFFICE

GEORGE F. HANDLEY, OF GLENDALE, NEW YORK, ASSIGNEE TO ROYAL TYPEWRITER COMPANY, INC., OF NEW YORK, N. Y., A CORPORATION OF NEW YORK

TYPEWRITING MACHINE

Application filed October 10, 1927. Serial No. 225,230.

This invention relates to bichrome ribbon mechanism adapted to be used in connection with a shiftable platen and particularly designed so that the throw of the ribbon for both red and black will be substantially the same in both the upper and lower case positions of the platen. It is also so designed that the ribbon vibrator will start to move at the same point in the depression of the key lever for both the black and red zones of the ribbon. The mechanism may also be set to stencil position in which there is no movement of the vibrator upon the depression of the key levers.

Further features of the invention will be apparent from the following detailed description and the appended claims.

In the drawings:

Figure 1 shows a longitudinal section through the machine with parts in side elevation, showing the parts in position for printing from the black zone of the ribbon in the lower case position of the platen.

Figure 2 is a side elevation of the ribbon vibrator operating mechanism with the parts in position for writing black in the upper case position of the platen.

Figure 3 is a similar view showing the parts in position for writing red in the lower case position of the platen.

Figure 4 is a similar view with the parts in position for writing red in the upper case position of the platen.

Figure 5 is a similar view showing the parts set to stencil position and the platen in lower case position.

Figure 6 is a similar view with the platen in upper case position.

In all of the views the normal position of the parts is indicated in full lines and the operated position by dot and dash lines. The invention is illustrated as applied to the Royal portable machine, although it is adaptable for use in various constructions.

There is illustrated a main frame A, a shift

frame B on which travels a carriage C supporting a platen D. Key levers E are connected by mechanism including front links F and links G to the heels of the type bars H pivotally mounted in a type segment K. 50 The ribbon is carried by the usual ribbon vibrator L. The rear ends of the key levers underlie a universal bar M supported by bars on a rock shaft N, which rock shaft has an upwardly extending arm O connected by a link P to a member R pivoted on the rear of the machine. The mechanism thus far illustrated is that commonly employed in the Royal portable machine.

The ribbon vibrator L is pivoted at 1 to an actuator 2 which is pivoted at 3 to the shift frame B. This actuator has a depending arm 4 to which is connected one end of a spring 5, the other end of which is connected to the shift frame and serves to draw an ear 6 of the actuator against an adjustable eccentric stop 7 carried by the shift frame which determines the normal position of the actuator 2. The actuator also has a second depending arm 8 having two contact surfaces *a* and *b* 70 at an angle to each other and also having a broadened outer end *c*.

Pivoted on the member R which is actuated each time a key lever is depressed, is a link 9 which is pivoted at its other end at 10 75 to a short link 11 in turn pivoted at 12 to an arm 13 mounted on a shaft 14. This shaft may be turned manually as in the present Royal portable construction or in any other desired manner and no specific means for 80 turning the same has, therefore, been illustrated. This shaft also carries rigidly thereon a stop member 15 having two stop surfaces *d* and *e*. The link 9 carries intermediate its ends a post 16 having a cut away side as 85 indicated at 17 for a purpose hereinafter set forth.

When the parts are in the full line position of Figure 1, it is to be noted that the post 16 is in position to engage with the surface *a* 90

- of the arm 8 which is located at a greater distance from the pivotal point 3 of the actuator 2 than is the surface *b*. The movement of the link 9 which occurs upon the 5 depression of any key will bring the post 16 into contact with the surface *a*, and move the actuator through a distance sufficient to bring the upper or black zone of the ribbon into operative relation to the type when at 10 the printing point. At the end of this movement, the upper edge of the actuator 2 will contact with the stop surface *d* as shown in dotted lines in Figure 1 and thus prevent any overthrow of the ribbon.
- 15 When the platen is shifted to upper case position it is to be noted that the actuator 2 and the parts to which the upper end of the link 9 is connected all shift upwardly with the platen. The lower end of the link 9, however, is connected to the part *R* carried by the frame of the machine and moves but very slightly with the platen shift movement. The parts then take up the position shown in full lines in Figure 2 in which it will be 20 noted that the post 16 is still in position to engage the operative face *a* of the arm 8, but is a little further removed from the pivotal axis 3 of the actuator than in the Figure 1 position. The link 9, however, which has a substantially endwise movement in its operation lies in a different line and the resulting movement of the ribbon will be substantially the same and to the same extent as when the parts are in the lower case position of Figure 1.
- 25 At the end of the movement, the actuator 2 contacts with the stop face *d* to limit the movement of the actuator and prevent overthrow of the ribbon.
- When it is desired to use the red zone of 30 the ribbon the shaft 14 is turned and thus not only changes the position of the arm 13, link 11 and of the pivotal point 10 between the links 9 and 11, but moves the stop 15 to the position shown in Figure 3. It will be noted that the movement thus described has 35 brought the post 16 up to a point where it will contact with the operative surface *b* of the arm 8 which is much closer to the axis 3 of the actuator than is the surface *a* and, therefore, the same movement of the link 9 will produce a greater movement of the ribbon vibrator and bring the lower or red zone 40 of the ribbon into printing position. At this time the actuator 2 contacts with the stop surface *e* of the stop 15 to prevent overthrow.
- When the platen is now shifted to upper case position the parts take up the position shown in Figure 4 in which the stop 16 is still 45 in position to engage the operative surface *b* but is slightly further from the pivotal axis 3 than in the Figure 3 position. However, the shift movement has changed the line of movement of the link 9 as above described so that 50 the resultant movement of the parts upon de-

pression of a key will produce the same operation of the ribbon.

In all four positions thus far described, it is to be noted that the post 16 is located substantially the same distance from engaging 70 faces *a* and *b* of the arm 8 of the actuator and since the link 9 begins to move at the same point in the depression of a key lever regardless of whether the platen is set for upper or lower case and of whether the ribbon vibrating mechanism is set for red or black, it will be obvious that the movement of the ribbon will be uniform in all cases, that is, it will start its movement at the same point in the depression of the key and will 75 reach its limit of movement before the type bar comes to the printing position.

If it is desired to make a stencil sheet, at which time the ribbon is not to be used, the shaft 14 is rotated in the opposite direction 80 from the Figure 1 position to that shown in Figure 5. This will move the arm 13, link 11 and link 9 to a position such that when the link 9 is operated, the cut away portion of the post 16 will just pass the lower 90 end of the arm 8 as shown in dotted lines in Figure 5 and produce no movement whatever of the ribbon actuator. If the platen is shifted for upper case position, the parts would appear as shown in Figure 6 and the 95 post 16 will lie a considerable distance below the end of the arm 8 of the actuator 2. It may be noted that the lower end *e* of the arm 8 is broadened in order to prevent any 100 possibility of the post 16 passing the same when the parts are set for stencil position.

It will be obvious that the construction described and illustrated is a very compact mechanism which is simple but efficient in operation and by which the ribbon will be 105 moved the same distance regardless of whether the platen is in upper or lower case position and in which the ribbon will begin to move at substantially the same point in the depression of a key regardless of whether the 110 platen is in its upper or lower case position and of whether the mechanism is set to write from the red or the black zone of the ribbon. It is obvious that the construction is particularly adapted for machines in which the 115 ribbon vibrator shifts with the platen but a portion of the actuating mechanism is carried by the frame of the machine. However, the invention may be applied to other types of machines and various details may 120 be modified without departing from the spirit thereof so that the invention is to be regarded as limited only by the scope of the appended claims.

I claim as my invention:

1. Bichrome ribbon mechanism for a type-writing machine having a shifttable carriage and a universal bar, comprising a vibrator, an actuator therefor adapted to shift with the carriage, an arm on said actuator having 130

- two operative surfaces, an operating member movable independently of the universal bar and pivotally connected at one end to the frame of the machine and having a part adapted to engage one or the other of said operative surfaces, and means for varying the position of said operating member to change the zone of the ribbon presented at the printing point.
2. Bichrome ribbon mechanism for a typewriting machine having a shiftable carriage, comprising a vibrator, an actuator therefor adapted to shift with the carriage, an arm on said actuator having an operative surface, an operating member supported at one end from the frame of the machine and having a part adapted to engage said operative surface, said part also varying its position when the carriage is shifted but to a less extent than the actuator, the operating member however having a different path of travel when the carriage is shifted and the resultant effect being that the actuator moves the same distance in both upper and lower case positions of the carriage.
3. Bichrome ribbon mechanism for a typewriting machine having a shiftable carriage, comprising a vibrator, an actuator therefor adapted to shift with the carriage, and arm on said actuator having an operative surface, an operating link pivoted at one end to a member on the frame of the machine and at its other end to member carried by the shiftable carriage and having intermediate its ends a part adapted to engage said operative surface, said part also varying its position when the carriage is shifted but to a less extent than the actuator, the operating link having a different path of travel when the carriage is shifted and the resultant effect being that the actuator moves the same distance in both upper and lower case positions of the carriage.
4. Bichrome ribbon mechanism for a typewriting machine having a shiftable carriage, comprising a vibrator, an actuator therefor adapted to shift with the carriage, an arm on said actuator having an operative surface, an operating member supported at one end from the frame of the machine and having a part adapted to engage said operative surface, said part also varying its position when the carriage is shifted but to a less extent than the actuator, the operating member however having a different path of travel when the carriage is shifted and the resultant effect being that the actuator moves the said distance in both upper and lower case positions of the carriage, said operating member being also movable to a position in which said part does not contact with the operative surface when it is moved.
5. Bichrome ribbon mechanism for a typewriting machine having a shiftable carriage, comprising a vibrator, an actuator therefor adapted to shift with the carriage, an arm on said actuator having an operative surface, an operating link pivoted at one end to a member on the frame of the machine and at its other end to a member carried by the shiftable carriage and having intermediate its ends a part adapted to engage said operative surface, said part also varying its position when the carriage is shifted but to a less extent than the actuator, the operating link having a different path of travel when the carriage is shifted and the resultant effect being that the actuator moves the same distance in both upper and lower case positions of the carriage, said operating link being movable to a position in which said part does not contact with the operative surface when it is moved.
6. Bichrome ribbon mechanism for a typewriting machine having a shiftable carriage, comprising a vibrator, an actuator therefor adapted to shift with the carriage, an arm on the actuator having two operative surfaces arranged at an angle to each other and at different distances from the axis of the actuator, an operating member having a part adapted to engage said surfaces, and means for moving said operating member so that said part will engage one or the other of said surfaces at substantially the same point in the depression of the key lever for both upper and lower case positions of the carriage.
7. Bichrome ribbon mechanism for a typewriting machine having a shiftable carriage, comprising a vibrator, an actuator therefor adapted to shift with the carriage, an arm on the actuator having two operative surfaces arranged at an angle to each other and at different distances from the axis of the actuator, an operating member having a part adapted to engage said surfaces, and means for moving said operating member so that said part will engage one or the other of said surfaces at substantially the same point in the depression of the key lever for both upper and lower case positions of the carriage, said means also moving said operating member to a position in which the part will not engage either of said surfaces when a key is operated.
8. Bichrome ribbon mechanism for a typewriting machine having a shiftable carriage, comprising a vibrator, an actuator therefor adapted to shift with the carriage, an operating link supported at one end from the frame of the machine and at the other end from the shift frame, and means for moving the latter end of the link to different positions so that the link moves in different paths for red and black but engages the actuator at substantially the same point in the depression of the key lever.
9. Bichrome ribbon mechanism for a typewriting machine having a shiftable carriage and a universal bar, comprising a vibrator,

an actuator therefor adapted to shift with the carriage, an arm on said actuator having two operative surfaces, an operating member movable independently of the universal bar 5 and pivotally connected to the frame of the machine and having a part adapted to engage one or the other of said operative surfaces, and means operable when the carriage is shifted for varying the position of said 10 operating member to change the zone of the ribbon presented at the printing point.

In testimony whereof, I have hereunto subscribed my name.

GEORGE F. HANDLEY.
